Claims priority, application Germany Aug. 28, 1953

9 Claims. (Cl. 260—459)

The present invention relates to new tropic acid derivatives and more particularly to bicycloalkyl substituted tropic acid compounds, and to a process of making same.

It is one object of the present invention to provide new and valuable amino alkyl esters of tropic acid derivatives which are characterized by a bicycloalkyl substituent carrying the hydroxyl group of tropic acid.

Another object of the present invention is to provide valuable acid addition salts of said amino alkyl esters of said tropic acid derivatives.

A further object of the present invention is to provide quaternary ammonium compounds of said amino alkyl esters of said tropic acid derivatives.

Still another object of the present invention is to provide a simple and convenient process of making such new and valuable amino alkyl esters of said tropic acid derivatives and acid addition salts and quaternary ammonium compounds thereof.

Other objects of the present invention and advantageous features thereof will become apparent as the description proceeds.

The new derivatives of tropic acid according to the present invention correspond to the following formula

40

wherein R₁ is a saturated or unsaturated bicycloalkanol group having the hydroxyl group at the carbon atom adjacent to the bridge C atom of the bicyclo while R₂ is an amino lower alkyl group the amino group thereof being substituted by lower alkyl groups. Their acid addition salts and the quaternary ammonium compounds thereof possess surprisingly high spasmolytic properties of considerably prolonged activity. They are of comparatively low toxicity and cause only insignificant side-reactions.

The new compounds are produced according to the process of this invention by reacting the organo-metal compounds of salts of phenyl acetic acid, for instance, their alkali salts, with saturated or unsaturated bicycloalkanol compounds of phenyl acetic acid are produced. Said compounds have the hydroxyl group at the carbon atom of the bicycloalkyl ring system adjacent to the CH group of phenyl acetic acid. Subsequently, the resulting bicycloalkanol derivatives of phenyl acetic acid are converted into the corresponding lower alkyl substituted amino lower alkyl esters, for instance, by reacting said bicycloalkanol substituted phenyl acetic acid compounds with lower alkyl substituted amino lower alkyl halogenides. The resulting esters are then converted either into their acid addition salts or, by reaction with quaternizing agents, such as alkyl halogenides, dialkyl sulfates, and others, into their quaternary ammonium compounds.

2

For instance, the diethylamino ethyl ester of (2-hydroxy bicyclo(2,2,1)heptyl-2) phenyl acetic acid is obtained by reacting bicyclo(2,2,1)heptanone-2 with the sodium salt of the bromo magnesium phenyl acetic acid and converting the resulting free acid into the corresponding diethylamino ethyl ester. Said ester, if desired, is subsequently converted into the quaternary ammonium salt.

Most of the amino alkyl esters of bicyclically substituted tropic acids are liquid substances which, however, can readily be recovered and isolated from the reaction mixture in the form of their readily crystallizing addition salts with inorganic or organic acids. When using such acid addition salts for therapeutical purposes, of course, only such acids are combined with said esters which are compatible to the human system and do not produce toxic effects. Suitable for such purposes are the hydrochlorides, and salts with hydrobromic, sulfuric, phosphoric, nitric, citric, tartaric, malic, maleic, malonic, succinic, benzoic, salicylic, mandelic, p-amino salicylic, phthalic, isonicotinic acid, penicillin in its acid form, and others may also be produced and employed for therapeutic purposes.

The quaternary ammonium compounds of bicyclically substituted tropic acids according to the present invention are also, in most instances, water soluble and readily crystallizing compounds.

The following examples serve to illustrate the present invention without, however, limiting the same thereto.

65

(2-hydroxy bicyclo(2,2,1)heptyl-2) phenyl acetic acid (I)

(I)

79.6 g. of finely pulverized dry sodium salt of phenyl acetic acid are introduced while strongly cooling, within 2 hours, into an ethereal solution of isopropyl magnesium bromide whereby the organo-magnesium compound of phenyl acetic acid is formed. During said reaction propane is developed. The ethereal isopropyl magnesium bromide solution is prepared by reacting 21.0 g. of magnesium shavings with 111 g. of 2-bromo propane in 700 cc. of dry ether.

55.0 g. of bicyclo(2,2,1)heptanone-2 (C₇H₁₀O) in 450 cc. of dry ether are added drop by drop to said organo-magnesium compound of the sodium salt phenyl acetic acid. The reaction is completed by heating under reflux. The reaction mixture is treated with dilute hydrochloric acid in the cold, the ethereal layer is separated and the free acid is removed therefrom by means of dilute sodium hydroxide solution. Addition of dilute hydrochloric acid to the aqueous solution of the sodium salt precipitates the bicyclically substituted phenyl acetic acid in the form of a viscous oil which completely solidifies after some time. The acid C₁₅H₁₈O₃ of the above given Formula I crystallizes from a mixture of acetone and ether (2:1) in needles arranged in clusters which melt at 170° C. The yield is 65% to 75% of the theoretical yield.

3

(2-hydroxy bicyclo(2,2,1)heptyl-2) phenyl acetic acid diethylamino ethyl ester hydrochloride (II)
and

(2-hydroxy bicyclo(2,2,1)heptyl-2) phenyl acetic acid diethyl methyl ammonium ethyl ester methosulfate (III)

and

123 g. of the acid $C_{15}H_{18}O_3$ are introduced into a solution of 11.5 g. of metallic sodium in 400 cc. of propanol-2. 86 g. of diethylamino ethyl chloride hydrochloride in 400 cc. of propanol-2 are added thereto. The mixture is boiled under reflux for 36 hours. After the sodium chloride formed is removed, the solution is concentrated by evaporation on a water bath under reduced pressure. The residue is treated with dry ether yielding thereby the hydrochloride of the diethylamino ethyl ester of the 30 above given Formula II ($C_{21}H_{31}O_3N.HCl$). Said hydrochloride crystallizes from ethyl acetate in slightly hygroscopic elongated needles melting at 132.5° C. The yield is 75% of the theoretical yield.

To convert said tertiary base into the methosulfate, 34.5 g. of the free base, obtained by carefully neutralizing an aqueous solution of its hydrochloride with sodium-bicarbonate solution and extracting the free base with ether, are dissolved in 250 cc. of dry ether. 15.1 g. of dimethylsulfate are added to said solution. After standing for some time, the quaternary ammonium salt of the above given Formula III precipitates almost quantitatively in solid form. It is readily soluble in water, methanol, and acetone, slightly soluble in ethyl acetate, and insoluble in ether. On recrystallization from a mixture of methyl acetate and ethyl acetate (1:1) it is obtained in massive druses melting at 114.5° C.

A small amount of a modification of said salt is obtained which modification crystallizes from a mixture of ethanol and ethyl acetate in hexagonal leaflets of the melting point 133° C. Total yield: 85% to 90% of the theoretical yield.

Reacting the free base of Formula II with methyl bromide, in place of dimethyl sulfate, and otherwise proceeding in the same manner as described hereinabove, yields the corresponding 2-(hydroxy bicyclo(2,2,1)heptyl-2) phenyl acetic acid diethyl methyl ammonium ethyl ester bromide.

EXAMPLE 2

(2-hydroxy- Δ_5 -bicyclo(2,2,1)heptenyl-2) phenyl acetic acid (IV)

4

79.6 g. of the sodium salt of phenyl acetic acid are converted as described in Example 1 into the corresponding organo-magnesium compound. Said compound is reacted with 54 g. of Δ_5 -bicyclo(2,2,1)heptenone-2 (C_7H_8O) in 450 cc. of ether. The reaction mixture is worked up as described in Example 1. The unsaturated acid $C_{15}H_{18}O_3$ of the above given Formula IV is obtained. Said acid, on recrystallization from a mixture of acetone and petroleum ether (2:1), crystallizes in the form of long prisms melting at 148.5° C. Yield: 20% to 30% of the theoretical yield.

(2-hydroxy- Δ_5 -bicyclo(2,2,1)heptenyl-2) phenyl acetic acid diethylamino ethyl ester hydrochloride (V)
and

(2-hydroxy- Δ_5 -bicyclo(2,2,1)heptenyl-2) phenyl acetic acid diethyl methyl ammonium ethyl ester bromide or methosulfate (VI), respectively

and

122 g. of the free acid $C_{15}H_{18}O_3$ are introduced according to Example 1 into a solution of 11.5 g. of metallic sodium in 400 cc. of propanol-2. Said solution is boiled under reflux with 86 g. of diethylamino ethylchloride hydrochloride in 400 cc. of propanol-2 for 36 hours. The reaction mixture is then worked up according to the procedure described in Example 1. The resulting hydrochloride of the diethylamino ethyl ester $C_{21}H_{31}O_3N.HCl$ of the above given Formula V is a slightly hygroscopic salt which crystallizes from ethyl acetate in prisms melting at 103° C. Yield: 60% to 70% of the theoretical yield.

The methobromide of the quaternary ammonium compound $C_{22}H_{35}O_3NBr$, which melts at 130.5° C., is obtained by addition of 9.5 g. of methyl bromide to 38.0 g. of the tertiary base in ethereal solution. It is readily soluble in water and methanol, slightly soluble in acetone, and insoluble in ether. Yield: 90% of the theoretical yield.

The methosulfate $C_{22}H_{35}O_7NS$ of the above given Formula VI is obtained in a similar manner from the tertiary base with dimethyl sulfate. It crystallizes from a mixture of acetone and ether (2:1) in small leaflets of the melting point 120-121° C. Yield: 85% to 95% of the theoretical yield.

EXAMPLE 3

(2-hydroxy bicyclo(2,2,1)heptyl-2) phenyl acetic acid dimethylamino ethyl ester hydrochloride (VII)

(VII)

74 g. of (2-hydroxy bicyclo(2,2,1)heptyl-2) phenyl acetic acid $C_{15}H_{18}O_3$ obtained according to Example 1 are dissolved in 240 cc. of propanol-2. Said solution is added to a solution of 6.9 g. of metallic sodium in 240 cc. of propanol-2. 43.2 g. of dimethylamino ethylchloride hydrochloride are added thereto and the mixture is boiled under reflux for 36 hours. The reaction mixture is worked up in a similar manner as described in Example 1, yielding the hydrochloride of the corresponding dimethylamino ethyl ester $C_{19}H_{27}O_3N.HCl$ of the above given Formula VII. On recrystallization from a mixture of methanol and ether (1:1) said hydrochloride is obtained in the form of crystals melting at 143° C. Yield: About 70% of the theoretical yield.

The tertiary base prepared from said hydrochloride is reacted with the required amount of dimethyl sulfate in ethereal solution and yields the quaternary ammonium methosulfate $C_{21}H_{33}O_7NS$ which, on recrystallization from a mixture of methyl acetate and ethyl acetate (1:1), melts at 145° C. Yield: 80% to 85% of the theoretical yield.

EXAMPLE 4

(2-hydroxy bicyclo(2,2,1)heptyl-2) phenyl acetic acid-1,3-diethylamino propyl ester hydrochloride (VIII)

80.7 g. of the sodium salt of (2-hydroxy bicyclo(2,2,1)heptyl-2) phenyl acetic acid are reacted with 56 g. of 1,3-diethylamino propylchloride hydrochloride and the reaction mixture is worked up in a similar manner as described in Example 1. The resulting hydrochloride of 1,3-diethylamino propyl ester $C_{22}H_{33}O_3N.HCl$ of the above given Formula VIII crystallizes from a mixture of acetone and ether (1:2) in the form of elongated prisms of the melting point 111-113° C. Yield: 75% of the theoretical yield.

(2-hydroxy bicyclo(2,2,1)heptyl-2) phenyl acetic acid-1,3-diethyl methyl ammonium propyl ester methosulfate (IX)

The free base $C_{22}H_{33}O_3N$ prepared from said above mentioned hydrochloride is reacted with dimethyl sulfate in ethereal solution and yields, in a similar manner as described in the preceding examples, the corresponding methosulfate $C_{24}H_{39}O_7NS$ of the above given Formula IX which crystallizes from a mixture of methyl acetate and ethyl acetate in tetragonal laminae melting at 103-105° C. Yield: 80% to 90% of the theoretical yield.

In place of bicyclo(2,2,1)heptanone-2 and Δ_5 -bicyclo(2,2,1)heptenone-2 used as bicyclo-alkanones in the preceding examples there may be employed equimolecular amounts of other bicycloalkanones, such as bicyclo(2,2,2)octanone.

In place of the sodium salt of phenyl acetic acid used in the production of the organo-magnesium compounds of said acid, there can be used equimolecular amounts of other alkali salts, such as the potassium or lithium salts, or of other salts of said acid, such as the calcium,

barium, magnesium salts thereof. The alkali salts, however, are the most preferred salts since they more readily react with the organo-metal compound than the other salts.

5 In place of dimethylamino ethyl chloride, diethylamino ethyl chloride, and diethylamino propyl chloride there may be used equimolecular amounts of other lower dialkylamino lower alkylhalogenides, such as di-isopropylamino ethyl chloride or bromide, di-n-butylamino ethyl chloride or bromide, 1,3-dimethylamino propyl halogenides.

10 As quaternizing agents there may be used, in place of methyl bromide and dimethyl sulfate employed in the preceding examples, methyl iodide, ethyl bromide, diethyl sulfate, p-toluene sulfonic acid alkyl esters, and others.

15 As stated above the new compounds are highly effective spasmolytic agents. On account of their anticholinergic properties they are successfully used in the treatment of peptic ulcers.

20 (2-hydroxy bicyclo (2,2,1)heptyl-2) phenyl acetic acid diethyl methyl ammonium ethyl ester methosulfate of Example 1 has been found to be of particular therapeutic interest on account of its considerable suppressing effect upon gastric secretion and motility. In this respect it has considerable advantages over other agents used for this purpose and especially over the widely administered drugs atropine and methantheline bromide.

25 30 Its toxicity is much lower than that of atropine and is about the same as that of methantheline bromide. Its DL_{50} for the white mouse in on subcutaneous administration 230 mg. per kg. and on intravenous administration 17.1 mg. per kg.

35 Testing said compound for its spasmolytic action upon isolated guinea pig intestines according to the method of Magnus (i.e. suppression of convulsions caused by administration of 0.02 mg./kg. of histamine, 0.02 mg./kg. of acetylcholine, or 100.0 mg./kg. of barium chloride) showed that said compound is at least as effective as the most effective drug atropine while methantheline bromide is only about one half to two thirds as active as atropine.

40 Likewise, its antagonism towards acetylcholine and its inhibiting effect upon vagus irritation, determined on 45 cats under chloralose anesthesia by measuring the dose required to suppress the reduction in blood pressure caused by administration of 0.1 mg./kg. of acetylcholine and subjecting said animals to electric irritation, is considerably more pronounced than that of other drugs and is approximately the same as that of atropine.

45 50 Its suppressing effect upon bronchospasms caused by administration of 3-5 mg./kg. of pilocarpine to cats in chloralose anesthesia is greater than that of any other drug and even that of atropine. Said effect is also of considerably prolonged duration.

55 60 Its inhibiting power upon gastric secretion and motility of the small intestines was tested in dogs in dihydro-morphinone-sodium isobutyl bromo allyl barbiturate narcosis. 0.005 mg./kg. of carbamyl choline chloride was subcutaneously administered to said animals in intervals of half an hour. The drug to be tested was intravenously administered in a dose of 0.002 mg./kg. or 0.005 mg./kg., respectively, after the initial stomach acidity and the increase in acidity caused by the first carbamyl choline chloride injection were determined.

65 The gastric juice was withdrawn from the duodenum by means of a catheter in intervals of a quarter of an hour whereby before each withdrawal 20 cc. of N/10 hydrochloric acid was introduced into the stomach in order 70 to ensure that a quantity of liquid sufficient for titration can be withdrawn. (2-hydroxy bicyclo(2,2,1)-heptyl-2) phenyl acetic acid diethyl methyl ammonium ethyl ester methosulfate reduces gastric acidity, which 75 was increased by carbamyl choline chloride administra-

tion, to a much greater extent and has a much longer acidity reducing effect than any of the other tested drugs and also than methantheline bromide.

Compounds according to the present invention and especially said 2-hydroxy bicyclo (2,2,1)heptyl-2 phenyl acetic acid diethyl methyl ammonium ethyl ester methosulfate primarily inhibit the stimulatory effect of acetylcholine, in nervous transmission, upon nervous excitation of the nerve terminations of the parasympathetic portion of the autonomic nervous system and, thus, has an atropine-like effect while its blocking effect upon the ganglionic synapses in any part of the sympathetic or parasympathetic nervous system is probably only of a supplementary and supporting nature.

Compounds according to the present invention do not substantially affect the circulatory system.

The new compounds are therapeutically administered either in the form of tablets, pills, dragees, powders, solutions or other orally administrable preparations or they may be subcutaneously or intramuscularly injected in the form of sterile aqueous or saline solutions. The daily dose in the treatment of peptic ulcer is 30 to 60 mg, given orally three times in the form of 1 to 2 tablets containing 10 mg. per tablet, or 2.5 mg. dissolved in 1 cc. of saline solution are injected subcutaneously or intramuscularly to afford relief from pain. After the ulcer is healed, it is advisable to continue a maintenance dosage of about one half of the therapeutic dosage for some time so as to avoid recurrence.

The new compounds are preferably used in their dilute form, thus, allowing better and more economical use to be made thereof.

In the administration of such compounds in capsules as powders, a fine uniform dispersion of the active product throughout said powder is desirable. Such a fine dispersion can be achieved, for instance, by intimately mixing and milling the compound in a ball mill with a solid, pulverulent extending agent to the desired degree of fineness, or by impregnating the already milled, finely powdered, solid carrier with a mixture of the active compound in water or other suitable solvents, and then removing the water or solvent.

When preparing tablets, pills, dragees, and the like, and shaped solid preparations for oral administration, the commonly used diluting agents, binder, and the like, are employed, such as sugar, lactose, talcum, starch, bolus alba, and as binders, pectin, gelatin, gum arabic, methyl cellulose, yeast extract, agar, tragacanth, and others.

The content of active compound in such preparations may vary. It is, of course, of advantage, that the active compound be present in said preparations in such an amount that a suitable dosage will be ensured. The unit dose should contain not less than 0.1% of the active compound. The preferred amounts to be employed in tablets and like shaped solid preparations are between about 2% and about 10% of the weight on the unit. To use greater amounts is, of course, also possible although administration of suitable dosage becomes somewhat cumbersome.

Injectable preparations contain preferably between 0.2% and 0.5% of the active compound but may, of course, also contain larger amounts.

Many changes and variations in the reaction conditions, the reaction components, the methods of working up and of purifying the reaction products, the forms of preparations used in therapy and the like may be made by those skilled in the art in accordance with the principles set forth herein and in the claims annexed hereto.

I claim:

1. A tropic acid compound selected from the group consisting of a tropic acid ester of the formula

its acid addition salts, its quaternary methosulfate, and its quaternary lower alko bromide, whereby

R₁ in said formula is a member selected from the group consisting of the 2-hydroxy bicyclo(2,2,1)heptyl-2-group and the 2-hydroxy-Δ₅-bicyclo (2,2,1)heptenyl-2-group, said 2-hydroxy bicyclo (2,2,1)heptyl-2-group and said 2-hydroxy-Δ₅-bicyclo(2,2,1)heptenyl-2-group having the hydroxyl group at the carbon atom adjacent to the CH-group of said tropic acid compound, while

R₂ is an amino lower alkyl group selected from the group consisting of an N-ethyl substituted amino ethyl group, an N-methyl substituted amino ethyl group, an N-ethyl substituted amino propyl group, and an N-methyl substituted amino propyl group.

2. A substituted phenyl acetic acid of the formula

wherein R₁ is a member selected from the group consisting of the 2-hydroxy bicyclo(2,2,1)heptyl-2-group and the 2-hydroxy-Δ₅-bicyclo (2,2,1) heptenyl-2-group, said 2-hydroxy bicyclo (2,2,1) heptyl-2- and 2-hydroxy-Δ₅-bicyclo (2,2,1) heptenyl-2-groups having the hydroxyl group at the carbon atom adjacent to the CH-group of said phenyl acetic acid.

3. (2-hydroxy bicyclo(2,2,1)heptyl-2) phenyl acetic acid diethylamino ethyl ester hydrochloride

4. (2-hydroxy bicyclo(2,2,1)heptyl-2) phenyl acetic acid diethylamino ethyl ester

5. (2-hydroxy-Δ₅-bicyclo(2,2,1)heptenyl-2) phenyl acetic acid diethyl methyl ammonium ethyl ester methosulfate

6. (2-hydroxy bicyclo(2,2,1)heptyl-2) phenyl acetic acid diethyl methyl ammonium ethyl ester methosulfate

9

7. (2-hydroxy bicyclo(2,2,1)heptyl-2) phenyl acetic acid diethyl methyl ammonium ethyl ester bromide

8. The (2-hydroxy bicyclo(2,2,1)heptyl-2) phenyl acetic acid of the formula

10

9. The (2-hydroxy- Δ_5 -bicyclo(2,2,1) heptenyl-2) phenyl acetic acid of the formula
